UNITED STATES PATENT OFFICE.

WILLIAM C. BLUNDELL AND OLIVER W. SMITH, OF LOS ANGELES, CALIFORNIA.

AUTOMATIC WATER-FEED CONTROL FOR BOILERS.

1,318,642.

Specification of Letters Patent.

Patented Oct. 14, 1919.

Application filed October 8, 1918. Serial No. 258,280.

To all whom it may concern:

Be it known that we, WILLIAM C. BLUNDELL and OLIVER W. SMITH, citizens of the United States, residing in the city of Los Angeles, county of Los Angeles, and State of California, have invented certain new and useful Improvements in Automatic Water-Feed Controls for Boilers, of which the following is a specification.

10 Among the salient objects of our invention are:—

To provide a mechanism which is controlled by the water condition in the boiler for automatically supplying water to the boiler very slowly, with means for automatically increasing said supply of water to the boiler in case of an emergency, or if from any cause the water supply in the boiler falls below the mean water level; to 15 provide in a device of the character referred to an improved valve mechanism for controlling the supply of water to the boiler, or the supply of steam to the pump, as the case may be, said valve mechanism being 20 moved in one direction by the pressure medium, whether it be steam or water, and in the opposite direction by an expansion control member which operates against the pressure medium; to provide in a device 25 of the character referred to means for draining and blowing out sediment and other matter which may collect in the pipes and connections used, and, in general, to provide a simple, practical, and efficient device of the character referred to which is 30 automatic in its operation.

In order to fully explain our invention, we have illustrated one practical embodiment thereof on the accompanying sheets 40 of drawings, in which:

Figure 1 is a side elevation thereof;

Fig. 2 is a top plan view thereof;

Fig. 3 is an end view thereof from the left hand end of Fig. 1;

45 Fig. 4 is a sectional view thereof, taken on line 4—4 of Fig. 1;

Fig. 5 is an opposite end view of Fig. 1;

Fig. 6 is a diagrammatic view showing a steam boiler and a pump and our improved 50 device interposed therebetween;

Fig. 7 is an enlarged sectional view through the valve casing and valve showing the valve open to a maximum extent;

55 Fig. 8 is a sectional view taken on line 8—8 of Fig. 7;

Fig. 9 is a sectional view taken on line 9—9 of Fig. 7;

Fig. 10 is a sectional view of a connecting box, connected with the usual water column of a boiler; and

Fig. 11 is an enlarged side elevation, partly in section of a valve mechanism.

Fig. 12 is a fragmentary view showing how the valve mechanism can be connected in the steam supply pipe from boiler to 65 pump, instead of in the water supply pipe from pump to boiler as shown in Fig. 11.

Referring now more in details to the drawings, 1 designates a connecting box, or casing having upper and lower chambers 70 2 and 3, connected, respectively, by means of pipes 4 and 5 to the boiler B, preferably through the usual water column, designated C, in Fig. 6. A drain pipe 7 with valve 8 is connected to the lower end of said casing 1, 75 and at its upper end said casing is provided with a plug 9. Connected to the upper chamber 2, of said box or casing 1 is a flexible tube 10, which connects at its opposite end with a coupling 11, on the end 80 of a brass expansion pipe 12, the opposite end of which connects with the chamber 3, of said box or casing 1, said pipe 12 being slightly inclined downwardly for drainage purposes. Under normal conditions steam 85 from the upper part of the boiler will find its way through the pipe 4 into the chamber 2 and into the flexible tube 10, while water from the boiler enters pipe 5, the lower chamber 3 of the casing 1, and the brass 90 pipe 12. Should the water fall below the mean level, or to such an extent that the steam from the pipe 10 shall fill the pipe 12, forcing the water out of the same, said pipe 12 will be expanded by the heat of said 95 steam and will move a thrust pin 14 longitudinally for a purpose hereinafter described.

A valve casing 15 is connected to the box or casing 1, by means of connecting rods 16, 100 16, as shown, said valve casing being also supported on the boiler by means of bracket members 17, 17, shown in Fig. 6. Said valve casing 15 is provided with a partition 15^a, for dividing the same into two chambers 18 105 and 19, as clearly shown in Fig. 7. A water supply pipe 20 connects through the upper side of the casing 15 and with a pump P, and discharges into said chamber 18. A pipe 21 leads from the chamber 19, of said 110

casing to the boiler. A by-pass 22 connects the pipe 20, around the valve casing 15, with the pipe 21, said by-pass having as a part thereof a valve 23. Said by-pass, as here shown, connects with a T 24 in said pipe, as shown in Fig. 3. Also connected with said T 24 is a drain pipe 25, provided with a valve 26. By this arrangement it will be seen that water from the pump, through pipe 21, can be allowed to pass through the by-pass 22 in any desired amount, depending upon the adjustment of the valve 23 therein. This can be regulated so that just sufficient water from the pump 15 through pipe 20, by-pass 22, and pipe 21, to the boiler will be allowed to pass to keep the pump barely moving.

We will next describe the mechanism by which a larger quantity of water is automatically supplied to the boiler through the pipe 20, the valve casing 15, and the pipe 21.

Referring to Figs. 7 and 11, a valve body 27 is mounted through the outer wall of the valve casing 15, being held in place by means of a bushing 28, said valve body having a chamber 29 therein into which open a series of inlets 30, 30. Said valve body terminates in a reduced portion 27^a, the inner end of which is slotted to make the extensions 27^b. Mounted upon said reduced portion 27^a, is a cap 31 secured thereto by means of set screws 32, 32, shown in Fig. 7, said cap 31 having an opening and valve seat 31^a, in its outer end. A valve ball 33 is mounted in the reduced portion 27^a of said valve member 27, and is free to roll into the opening and valve seat 31^a, so as to close the same when moved in that direction by pressure from the opposite side, thus closing the passage from chamber 18 of said valve casing to chamber 19 of said valve casing. The thrust rod 14, connected with the expansion tube 12, projects through a bushing 34, into a chamber 19, and in proximity to said valve ball 33, whereby when said expansion tube 12 is expanded and extended, under heat from steam entering the same, said thrust rod 14 is moved inwardly, as shown in Fig. 7, sufficiently to move said ball valve 33 away from the valve seat 31^a, thus allowing water or steam, as the case may be, to pass from the pipe 20, through the chamber 18, the inlets 30, the chamber 29, and around said ball, between the extensions 27^b through said opening 31^a, to the chamber 19, and thence to the pipe 21, and to the boiler, thus increasing the supply of water from the pump to the boiler.

In addition to the supply which has been permitted to pass through the by-pass 22 in said boiler:

If it is ever desired to connect the valve mechanism 15 and its pipes 20 and 21, into the steam supply pipe from boiler to pump,

this can be done as indicated in Fig. 12, in which the steam pipe 35 is connected to the pipes 20 and 21, so that steam from the boiler passes through pipe 35, thence through pipe 20, and into the valve casing 15, through the valve mechanism, and out through the pipe 21 and on through pipe 35 to the pump. Therefore, when the water in the boiler gets low, as before described, and the expansion tube 12 operates to open the ball valve 33, as before described, an increased steam supply is permitted to pass through the valve mechanism to the pump and increase the action of the pump, thus supplying more water to the boiler, with the result that the expansion tube is cooled and the valve 33 is closed by the pressure of the steam behind it.

In either case, whether it is steam passing through the valve mechanism, or water, when the ball valve 33 is closed, only sufficient water, or steam, as the case may be, is permitted to pass through the valve mechanism and the by-pass pipe 22 and its valve 23, to barely let the pump move, if it is water going through said by-pass, or to barely operate the pump, if it is steam going through said by-pass.

Thus our mechanism is connected up in such a manner as to automatically regulate the water supply to the boiler and to actually prevent accidents by low water in the boiler.

We are aware that changes in details can be made without departing from the spirit of our invention and we do not, therefore, limit the invention to these details as here shown for purposes of illustration, except as we may be limited by the hereto appended claims.

We claim:

1. In a device of the character shown and described comprising in combination with a boiler, a casing having upper and lower chambers connected with said boiler, a valve casing with a partition forming two chambers therein, a valve mechanism supported in said partition and controlling communication between the chambers of said valve casing, an expansion tube connected at one end with the lower chamber of said first mentioned casing and at its other end connected within said valve casing for moving said valve mechanism to open communication between the two chambers in said valve casing, and a flexible tube connecting the upper chamber of said first mentioned casing with the end of said expansion tube adjacent said valve casing.

2. In a device of the character shown and described, in combination, a casing having upper and lower chambers therein, means for connecting said chambers with a boiler, a flexible tube connected at one end with the upper chamber of said casing, an expan-

- sion tube connected at one end with the lower chamber of said casing, said flexible tube and expansion tube being connected at their other ends, a valve casing having a 5 partition therein forming two chambers, a cylinder with valve mechanism therein extended through said valve casing and said partition and controlling communication between the chambers in said valve casing, and 10 an operating member extended from the end of said expansion tube through said valve casing and adapted to open said valve mech-
- anism to establish communication between the chambers of said valve casing, substantially as described. 15

Signed at Los Angeles, Los Angeles county, California, this 16th day of September, 1918.

WILLIAM C. BLUNDELL.
OLIVER W. SMITH.
